UNITED STATES PATENT OFFICE.

HANS PETERSEN, OF DAVENPORT, IOWA, ASSIGNOR TO THE LINOGRAPH COMPANY, A CORPORATION OF IOWA.

MATRIX-DISTRIBUTING MECHANISM.

1,317,098.

Specification of Letters Patent. Patented Sept. 23, 1919.

Application filed August 27, 1918. Serial No. 251,684.

To all whom it may concern:

Be it known that I, HANS PETERSEN, a citizen of the United States, residing at Davenport, in the county of Scott and State of Iowa, have invented certain new and useful Improvements in Matrix-Distributing Mechanism, of which the following is a specification.

This invention relates to improvements in matrix distributing mechanism for linotype machines.

In machines of this nature, after the casting operation, difficulty is experienced in returning the thicker matrices to the magazine, the larger or thicker matrices owing to their size and their movement along the distributor bar at right angles to the chambers of the magazine, in dropping from the distributor bar strike the partition walls of the magazine, making it necessary to provide an excess of space between the partition walls of the magazine. It is the object of the present invention to overcome this difficulty, and to this end the invention comprehends a matrix provided with a beveled face extending completely across its lower end and located at the forward side of the matrix facing in the direction of travel thereof along the distributor bar, said beveled face being adapted to engage the partition walls of the magazine and acting to guide the matrix into the channel entrance. It will be understood that this construction is designed chiefly for the thicker matrices and that the invention comprehends employing thick matrices of this form with thin matrices as commonly constructed having rectangular shaped lower ends, and an important feature of the invention also resides in the provision of a special construction of distributor lift capable of lifting either a thick beveled matrix or a thin un-beveled matrix and functioning in the usual way to lift only a single matrix at each lifting movement.

The invention, with other objects and advantages thereof, and the particular construction, combination, and arrangement of parts comprising the same will be understood from the hereinafter contained detail description when considered in connection with the accompanying drawings forming part hereof and illustrating one embodiment of the invention.

In the drawings:

Figure 1 is a side elevation of distributor mechanism including a distributor lift constructed in accordance with the present invention.

Fig. 2 is a side elevation, on an enlarged scale, of the distributor lift engaging one of the thick beveled matrices.

Fig. 3 is a similar view showing the distributor lift engaging one of the thin un-beveled matrices.

Figs. 4 and 5 are detail views of one of the thick beveled matrices.

Referring to a detail description of the drawings wherein like reference characters designate corresponding parts throughout the several views, 1 designates the distributor box, 2 the conveyer screws, 3 the distributor bar and 4 the magazine having partition walls 4', all of usual construction, the matrices after the casting operation being fed from the distributor box 1 to the conveyer screws and moved thereby along the distributor bar from the magazine to their respective channels or compartments of the magazine.

Referring particularly to Figs. 4 and 5 of the drawings, A designates one of the thick matrices having the usual supporting ears a, the matrix character a' on one edge face thereof, and the distributor teeth a² at its upper end. In accordance with the present invention the matrix A is provided with a beveled face b extending completely across its lower end. The beveled face b is located at the forward or front side of the matrix facing in the direction of travel of the matrix along the distributor bar 3 indicated by the arrow. These beveled faces b of the thick matrices, are adapted, upon the dropping of the matrices from the distributor bar, to engage the partition walls 4' of the magazine so that, if, as the tendency is, the matrices do not drop from the bar at the intended place along the same but are carried slightly beyond this point, they will not catch or hang upon the partition walls 4' of the magazine but the beveled faces of the matrices, disposed at the front side thereof facing the direction of travel will engage the partition walls and serve to guide the matrices into the entrance of the particular channel or compartment, this construction permitting of the use of matrices

of practically the size of the space in the channel into which they are to be received without requiring any modification whatever of the magazine structure.

5 An important feature of the invention also resides in the provision, in combination with the improved matrix structure, of a special construction of distributer lift capable of operating with both styles of matrices, the 10 thick beveled ones and the matrices of minimum width having rectangular shaped lower ends, the distributer lift operating in the usual manner to lift a single matrix at each lifting operation. Referring particu- 15 larly to Figs. 1, 2 and 3 of the drawings, 6 designates a distributer lift constructed in accordance with the invention. The lift 6 is in the form of a blade or finger having a matrix engaging part at its upper end comprising a straight shoulder portion 7 and a beveled lip 8 at one side thereof. The straight shoulder portion 7 is of a width equal to the minimum width of the thinnest matrices intended to be employed, and the 20 beveled lip 8 is formed to correspond to the bevel faces *b* of the thick matrices. As will be understood this construction of lift is capable of effectually performing its function with either the thin unbeveled matrix 25 or the thick beveled matrices. In operating upon the thin unbeveled matrices the straight shoulder portion 7 of the lift engages the straight bottom edge faces of the matrices, and in the case of the thick be- 30 veled matrices, the beveled lip 8 engages the beveled faces *b* of the matrices and the straight shoulder portion 8 engages the lower ends of the matrices beyond the beveled faces *b*. 35 40 Any suitable operating means may be employed for the distributer lift, to reciprocate the same at each revolution of the distributer screws. In the drawings I have shown the distributer lift 6 connected with one of the well known forms of lift operating means, said means comprising a vertically swinging rock arm 9 connected with a lever 10 actuated by a cam 11 mounted on

the rear upper conveyer screw and engaging a roller 12 journaled on the lever 9, the 50 distributer lift being secured at its lower end to the outer end of the vertically swinging arm 9.

While I have illustrated in the drawings a specific embodiment of the invention, it 55 will be understood that minor changes and variations in the particular construction shown as will appeal to those skilled in the art and falling within the scope of the appended claims may be practised without departing from the spirit of the invention. 60

What I claim is:

1. In a linotype machine the combination of distributer mechanism, including a distributer lift having a matrix engaging part 65 comprising a straight shoulder portion and an inclined lip at one side thereof and matrices having beveled faces extending completely across their lower ends at the forward side thereof facing in the direction 70 of travel of the matrices.

2. In a linotype machine, the combination of distributer mechanism including a distributer lift having a matrix engaging part comprising a straight shoulder portion and 75 an inclined lip at one side thereof, matrices having rectangular shaped lower ends and beveled faces extending completely across their lower ends at the forward side thereof facing in the direction of travel thereof. 80

3. In a linotype machine the combination of distributer mechanism including a distributer lift having a straight shoulder with a beveled lip at one side thereof, relatively 85 thin matrices having rectangular shaped lower ends, and relatively thick matrices having beveled faces extending completely across the lower ends thereof, said distributer lift being capable of lifting one at a time the matrices of minimum width having rectangular shaped lower ends and also the thick matrices having beveled faces at their lower ends. 90

In testimony whereof I affix my signature.

HANS PETERSEN.
